H. KOPPERS

COKING RETORT OVEN

Filed Aug. 31, 1921

FIG. 2.

FIG. 1.

Inventor:-

Heinrich Koppers

For: Monday, Clarke & Carpenter, Attn:

UNITED STATES PATENT OFFICE.

HEINRICH KOPPERS, OF ESSEN-RUHR, GERMANY, ASSIGNOR TO THE KOPPERS DEVELOPMENT CORPORATION, OF PITTSBURGH, PENNSYLVANIA, A CORPORATION OF PENNSYLVANIA.

COKING RETORT OVEN.

Application filed August 31, 1921, Serial No. 497,368, and in Germany November 7, 1919.

This invention relates to inclined chamber furnaces for the production of gas and coke with heat recovery.

Such inclined chamber furnaces, owing to their marked deviation from the rectangular co-ordinate system preferably for the whole procedure of coking, cause not only structural difficulties, but primarily also technical difficulties with respect to heating. In consequence of the different buoyancies at different levels of the chambers a uniform heating of places corresponding to each other in the chamber inclination, cannot be effected right away. For this reason even for example the furnace according to the American Patent No. 571,558 of Dods, in spite of being furnished with regenerators for the purpose of heat recovery, cannot be used, because the gases must seek their own path in the heating wall and can exert no regulating influence thereon, as also the regenerator owing to its structural union with the heating wall, quite apart from the fact that, due to the only partially free lower chamber opening, coking coal cannot be worked at all.

According to the invention, there is obtained for such inclined chamber furnaces, in spite of the varying buoyancy, a practically fully satisfactory uniformity in the heating, this being achieved by arranging the regenerators directly in parallel with the heating walls in the first place, and in the second place by dividing the latter into separate individually controllable heating passages, so that the flame and the waste heat gases are prescribed quite definite, compulsory paths. It is known that regenerators, which are traversed by the fuels to be preheated from bottom to top, and by the waste heat gases to be cooled from top to bottom, give uniform distribution or division in operation (see the article "Grundlagen fur das richtige Entwerfen von Ofenanlagen"—Rules for the correct design of furnace plant—in "Stahl und Eisen" 1913 page 860). This is due to the distributing or dividing effect produced by the fire-proof checkerwork of the regenerators, corresponding to a series of sieves spaced from each other, which effect occurs owing to the constantly occurring path deflections of the gases and the total resistance encountered. By the direct connection of such regenerators with the heating wall the thorough divi-

sion is thus maintained while with the draft reversal a certain equalizing of local irregularities occurs. Since the thus divided gases are prescribed definite compulsory paths in the heating channels, which are controllable by means of slides lying above the same, it is possible, not only to maintain this thorough division, but even to make it finer, for the side which at any time receives the waste heat is operated with regulation in the same way. In this manner the difficult task of uniformly heating inclined chamber furnaces is solved.

This distributing influence of the unidirectional buoyancy in inclined chamber furnaces is still further obviated according to the invention, and uniform heating improved, by cutting away the uppermost corner of the heating wall, otherwise in the form of an inclined parallelogram, so that in the upper corner of the waste gas collecting channel a member thereof runs horizontally over the heating channels, this waste gas collecting channel thus receiving on the whole an abrupt change in direction or bend. In this way the great difference in buoyancy at the two ends of this collecting channel can in all cases be essentially diminished.

This special arrangement of the heating wall receives its external embodiment by a corresponding cutting away of the upper corner of an inclined chamber furnace, so that a natural platform for the personnel is produced at this place. It is thus also possible to carry out the charging conveniently from this point in the manner known for horizontal chamber furnaces, since with the aid of charging trucks running on the platform the chambers can be charged through vertical filling openings. In this charging there forms at both sides a conical angle of repose which on one side corresponds to the inclination of the chamber, while on the other side a dead space is avoided by cutting away the upper corner also in the actual coke or coal chamber, this being done about in accordance with the angle of repose assumed by the coal, so that either a pentagonal cross-section or a cross-section in the form of a trapezium is produced. It is thus possible, to make the lie of the coal fit the bend or kink in the waste gas collecting channel, so that on the one hand the whole charge receives the necessary supply of heat, and on the other hand overheating owing

to heating spaces not filled by the charge is avoided.

In the accompanying drawing a constructional example of the subject matter of the invention is represented for the purpose of explanation, but not for the limitation of my invention to constructive details. In said drawing:

Fig. 1 is a transverse section through the furnace chamber, Fig. 2 is a similar parallel section through a heating wall.

Below the inclined furnace chamber 10 are arranged the regenerators 12 and 13 separated by an intermediate wall 11, and the regenerator 12 can be connected by pipe bends 14 either to the waste heat channel 15 or to the fresh air, while the regenerator 13 can be put into communication through the pipe bends 16 with the waste heat channel 17 or with the air. In the case of simultaneous preheating of gas and air, the regenerator chambers for the preheating of air alternate with those for the preheating of gas. If a partial heating with poor gas and rich gas is provided a separate supply channel for the non-preheated rich gas also has to be furnished. The regenerators 12, 13 are controlled in a known manner with half hourly reversal, whereby the cold air enters the regenerator 12 and the waste heat gases arrive in the waste heat channel 17 by way of the regenerator 13, whilst on reversal of the draft the regenerators 13 serve for preheating air and the waste heat gases flow through the regenerator 12 into the waste heat channel 15.

By means of nozzle like ducts 18 the regenerators 12 and 13 are directly connected to the heating passages 19 which have at their upper ends nozzle like constrictions 20 which can be controlled by slides 21 overlying the same, actuated by means of rods 22 which can be inserted through openings 23 in the furnace cover. While the most of these heating passages 19 are arranged stepwise with the inclination of the chamber, the uppermost heating passages, six in this case, are arranged on the same level so that the waste gas collecting channel 24 has here a bend from its sloping position into the horizontal. Thereby the most of the buoyancy difference is appreciably diminished in the waste gas channel 24. Corresponding to the fact that the coking chamber diverges downwardly to allow a ready loosening of the charge, the dividing of the heating wall, which is intended for the draft reversal, is not made in the middle but displaced downwards therefrom, so that corresponding to the greater corner coal space there, a greater amount of heat is supplied (see German Patent 150,117).

The gases developing in the chamber 10 are led upwards by a rising pipe 25 to the collector 26. On the platform 27, corre-

sponding to the bending of the waste gas channel 24 to the horizontal, run the charging trucks 28, which as in coke oven charging, charge the furnace chamber 10 through filling openings 29, the coal filling the chamber uniformly, the latter being arranged substantially parallel with the angle of repose of the coal. In order also to obviate dead spaces on the other side, the upper end of the chamber 10 is also sloped in accordance with the angle of repose by means of a wall 30, in such a manner that a pentagonal cross-section is obtained. Hereby in the first place a filling out of the chamber with coal corresponding with the purpose in view is provided, while also the necessary conditions as regards the heating are maintained. The finished charge can be extruded by a small extrusion machine operating through the opening 31, if automatic emptying does not occur on opening the lower door of the chamber.

In order not to cut into this service platform unnecessarily, access to the slides 21, for the short horizontal extent of the channel 24, can be made from the end through an opening 32, which can always be closed by a brick.

What is claimed is—

1. An inclined furnace chamber structure for producing gas and coke, comprising in combination: an inclined retort; vertical heating flues arranged alongside the lower end of said inclined retort having their lower ends arranged in an inclined plane substantially parallel to the plane of inclination of said retort; vertical heating flues arranged alongside the upper end of said inclined retort having their lower ends arranged in a substantially horizontal plane; a regenerator below and communicably connected with the vertical flues alongside the lower end of said retort; a regenerator below and communicably connected with the vertical flues alongside the upper end of 100 said retort, each of said regenerators being adapted to alternate for inflow and outflow; the regenerator for the vertical flues alongside the lower end of said retort having its upper part arranged stepwise, each step being directly connected with a vertical flue, and the regenerator for the vertical flues alongside the upper end of said retort having the major portion of its upper part in a single horizontal plane for direct connection with its vertical flues; a waste gas collecting channel above said vertical flues and communicably connected therewith, said channel being inclined throughout a portion of its length over the vertical flues alongside the lower end of said retort, and extending horizontally throughout a portion of its length over the vertical flues alongside the upper end of said retort; the furnace structure being formed to provide a charg- 120

ing platform over said horizontally extended portion of the waste gas collecting channel.

2. An inclined coking retort structure for producing gas and coke comprising, in combination: an inclined distillation chamber; vertical flues arranged alongside the lower end of said inclined distillation chamber having their lower ends arranged in an inclined plane substantially parallel to the plane of inclination of said chamber; vertical flues arranged alongside the higher end of said inclined distillation chamber having their lower ends arranged in a substantially horizontal plane; regenerators directly connected with said vertical flues, said regenerators underlying said flues and being adapted to alternate for inflow and outflow, one of said regenerators being communicably connected with the vertical flues alongside the lower end of the distillation chamber, the upper part of said one of said regenerators being arranged stepwise and each step directly communicating with a vertical flue; another of said regenerators being communicably connected with the vertical flues alongside the higher end of said distillation chamber, the upper part of said another of said regenerators being arranged horizontally to directly connect with the vertical flues thereabove; slides at the upper ends of said vertical flues for regulating the flow therefrom; a waste gas collecting channel above said vertical flues and communicably connected therewith and arranged to provide an inclined channel over the vertical flues alongside the lower end of the distillation chamber and a horizontal channel over the vertical flues alongside the higher end of the distillation chamber; said coking retort structure providing a horizontal platform above the horizontal portion of the waste gas collecting channel for charging the distillation chamber, said distillation chamber having the inner surface of its upper rear wall sloping downwardly and outwardly at a substantial angle to the vertical whereby to prevent dead gas spaces resulting from the charging of said distillation chamber.
3. An inclined coking retort structure as in claim 2, characterized in that the slides for the upper ends of the vertical flues along-

side the higher end of the distillation chamber are arranged in the horizontal portion of the waste gas collecting channel and the adjusting of the slides of said vertical flues may be effected from one end of the horizontal portion of the waste gas channel through an opening in the retort structure which can be closed by a brick, whereby the horizontal platform is not unnecessarily cut into.

4. A coking oven having, in combination: an inclined coking chamber; reversibly operable regenerators thereunder adapted to alternate for inflow and outflow; a series of upright heating flues alongside the coking chamber and communicating with said regenerators; a part of said series of heating flues being disposed alongside the lower portion of said inclined coking chamber and arranged stepwise at successive greater heights and having their lower ends arranged in an inclined plane substantially parallel to the plane of inclination of said chamber; and a part of said series of heating flues being disposed alongside the upper portion of said inclined coking chamber and arranged in a substantially horizontal plane one after the other and having their lower ends arranged in a substantially horizontal plane; a waste gas collecting channel communicably connecting the tops of the upright heating flues disposed alongside the lower portion of said distillation chamber with the tops of the upright heating flues disposed alongside the upper portion of said distillation chamber; said waste gas collecting channel having an upwardly inclined part over the stepwise flues and a horizontal part over the flues in said substantially horizontal plane; gas flow control means at the top of each of said upright heating flues for controlling the flow through each of the heating flues to and from said waste gas channel; and elongated vertically arranged access passages extending upwardly from above said waste gas channel through which the flow control means for the stepped flues may be adjusted.

In testimony whereof, I have hereunto set my hand this 25th day of July, 1921.

HEINRICH KOPPERS.
